UNITED STATES PATENT OFFICE.

FREDERIC A. DE LAY, OF CHICAGO, ILLINOIS.

PHONOGRAPH.

1,293,363.

Specification of Letters Patent. Patented Feb. 4, 1919.

Application filed October 19, 1917. Serial No. 197,396.

To all whom it may concern:

Be it known that I, FREDERIC A. DE LAY, a citizen of the United States, residing at Chicago, in the county of Cook and State of Illinois, have invented a certain new and useful Improvement in Phonographs, of which the following is a full, clear, concise, and exact description, reference being had to the accompanying drawings, forming a part of 10 this specification.

My invention relates to improvements in phonographs or machines for the reproduction of sound, and has for its object the provision of improved mechanism for automatically repeating the reproduction of a record and for automatically stopping the machine after the reproduction has been repeated a predetermined number of times.

In carrying out the objects of my invention I contemplate the provision of electro-magnetic devices which are automatically operated by the machine when the reproducing stylus assumes certain positions with respect to the record. I have shown in the 20 accompanying drawings the device of my invention applied to a phonograph wherein the tapered tube or tone arm is arranged to move only in a horizontal plane and wherein the tapered tube is connected with a sound 25 box crook which carries the reproducer. I wish it to be understood that the device of my invention may be utilized in connection with a phonograph wherein the tapered tube or tone arm is connected directly with the 30 reproducer and wherein the tone arm is raised whenever the stylus of the reproducer is moved out of engagement with the sound 35 grooves of the record.

I am aware of the fact that repeating 40 mechanism has been employed in connection with a phonograph, but such mechanism has been found commercially impracticable for several reasons; first, that the mechanism is too complicated and expensive in view of 45 the result or object for which it is intended; second, that it cannot be applied to the machines now in use or on the market; and third, that such mechanism cannot be employed for the reason that harm will result 50 either to the sound reproducer or to the record with which the reproducer cooperates. It is the primary object of the present invention to avoid all these shortcomings of the devices of the prior art and to provide 55 a commercially feasible device.

Although I provide mechanism for auto-

matically stopping the machine after a production has been repeated a certain predetermined number of times this automatic stop mechanism need not be employed if it 60 is desired to dispense with the same.

The entire mechanism for repeating and for automatically stopping the machine after a record has been replayed a number of times is mounted directly onto the motor 65 board and is arranged so that it can be applied to any standard phonograph. One of the important features of the present invention resides in the provision of an electric switch, either mounted on the tone arm 70 or having some actuating element mounted on the tone arm, the purpose of the switch being to close an electric circuit when the tone arm reaches a certain position with respect to the record and to maintain the circuit in closed condition until the tone arm 75 assumes a certain other position with respect to the record where a second operation of the switch takes place and the circuit is broken. 80

Another important feature of the present invention is the provision of an improved arm arranged to lift the reproducer from the record when the repeating operation takes place. This arm is constructed and 85 arranged so that it can be placed upon and removed from the machine whenever desired without the inconvenience of manipulating any screws, clamps, or similar devices.

In view of the fact that the other improved features of the present invention may be understood more clearly by reference to the accompanying drawings attention is directed to the drawings wherein:

Figure 1 is a fragmentary perspective 90 view of a phonograph provided with the reproducer of my invention;

Fig. 2 is a detail side elevational view of the tapered tube and sound box crook of Fig. 1 showing the repeating mechanism 100 mounted thereon;

Fig. 3 is a fragmentary plan view of the motor board shown in Fig. 1 illustrating the electric circuits employed for effecting the necessary operation of the electro-magnetic 105 devices;

Fig. 4 is an enlarged detail view of the automatic stop ratchet shown in Fig. 3;

Fig. 5 is a vertical cross sectional view taken along the line 5-5 of Fig. 2 looking 110 in the direction indicated by the arrows;

Fig. 6 is a detail view of the electro-mag-

netic device for applying the brake to the turn table after a record has been repeated a certain predetermined number of times;

Fig. 7 is a horizontal cross sectional view taken along the line 7—7 of Fig. 5 looking in the direction indicated by the arrows; and

Fig. 8 is a fragmentary perspective view of a modified form of switching mechanism which may be employed for controlling the operation of the repeating electro-magnet. Similar characters of reference refer to similar parts throughout the several views.

Referring first to Fig. 1, 9 illustrates the casing or framework which supports the motor board 10. This motor board in the class of phonographs represented by Fig. 1 carries on its underside the necessary motor for rotating the turntable 11 upon which the record to be reproduced is placed, the turntable being mounted upon and connected with its drive shaft 12 in any suitable manner. The tapered tube or tone arm is shown at 13 extending downwardly at 14 and communicating with the sound chamber or horn, if the phonograph be one employing a horn. The tone arm 13 is arranged to swing in a horizontal plane in the usual manner and is provided at its free end with a crook or gooseneck 15 the outer end of which carries the sound box or reproducer 16. The crook 15 is arranged to swing in a vertical plane about the point 17, shown in Fig. 2, there being a pivotal connection between the crook 15 and the tapered tube. The reproducer is arranged to carry the usual reproducing stylus shown at 18. By swinging the crook 15 in a counterclockwise direction (Fig. 2) the stylus 18 is moved out of engagement with the sound grooves of the record shown at 19.

Mounted around the tapered tube 13 is a bracket 20 which carries the electro-magnets shown at 21. The bracket 20 may be constructed in any desirable manner and may be attached to the tapered tube 13 in any convenient manner. In the drawings I have illustrated the bracket 20 as being stamped from sheet material and provided with the arms shown at 22 which extend around the tone arm and are connected at 23 to hold the bracket securely in place. On account of the outward taper of the tone arm there may be a tendency for the bracket 25 to move outwardly toward the restricted portion of the arm and to prevent such movement the bracket 20 is provided with the forwardly extending arm 24 which abuts against the front end of the tone arm 26 or the crook 15. The armature for the electro-magnets 21 is formed by the lever 26 which extends over the forward end of the tone arm and under the front end of the crook 15. There is no mechanical connection 65 necessary to hold the arm 26 in place other

than that shown in Fig. 2 so that the arm may be removed from or placed upon the reproducing element of the phonograph without any inconvenience. To hold the arm 26 in place so as to prevent lateral movement thereof the forwardly extending arm 24 of the bracket 20 may be provided with an upwardly extending retainer shown at 27. The forward end of the tone arm 13 forms a fulcrum for the lever 26 so that upon movement of the lefthand end of the lever (Fig. 2) in a downward direction the crook 15 will be swung upwardly to cause the reproducing stylus 18 of the reproducer to disengage the record.

Extending downwardly from the bracket 20 is an arm 28 to which is pivoted at 29 a switch member 30 (Fig. 5). This switch member carries an insulated pin or contact 31 and is provided with a pair of indentations shown at 32—32 in Fig. 7. These indentations are arranged to coöperate with and assume a position either on one side or the other of the projections shown at 33—33 carried by the downwardly extending arm 28. The arm 28 also carries the contact 34 adapted to coöperate with the contact 31 carried by the switch member.

Carried by the base board of the phonograph is a plate 35 to which is pivoted at 36 a stop lever 37 provided with a stop 38 and extending forwardly under the turntable 11 to coöperate with an index plate shown at 40. The front end of the lever 37 may be provided with a handle piece shown at 41 to facilitate setting of the lever. In view of the fact that the inner sound grooves of phonograph records terminate in different places with respect to the centers of the records it is necessary to adjust the stop lever 37 for each record played and to facilitate this adjustment the index plate 40 is provided which carries certain indicia, as shown in Fig. 3. The records are marked with certain indicia corresponding with the 105 indicia carried by the plate 40 so that the stop lever 37 may be set to its correct position each time a record is played by setting the lever to the character on the plate 40 corresponding to the character marked on the 110 record.

Pivoted to the plate 35 at 42 is a second lever 43 provided with a handle piece 44 to facilitate rotation of the lever about its pivot 42. The lever 43 and the lever 37 are pivoted to the plate 35 in a manner such that a certain amount of friction must be overcome before movement of either one of the levers can be effected. This frictional connection may be provided in any convenient way, as by interposing a friction washer between each one of the levers and the plate 35. The lever 43 carries an upwardly extending stud 45 (Fig. 4) which is rigidly fixed thereto. Rotatably mounted around 120

the stud 45 is a sleeve 46 attached to or forming part of a ratchet wheel 47. The ratchet wheel 47 is made of material such that it permits the flow of current therethrough. Extending through the ratchet 47 is an insulated plug 48 which at certain predetermined times is arranged to engage the two brushes shown at 49 and 50. To facilitate setting of the ratchet 47 or rotation of this member about the stud 45 the sleeve 46 is rigidly connected with the knurled finger piece 51 held in place by the screw 52.

The lever 43 has two upwardly extending pieces 53—53 through which extends a plunger 54 having pivoted thereto a pawl 55 arranged to coöperate with the ratchet 47 to advance the latter one step each time a record is repeated. To hold the plunger 54 normally in the position shown in Fig. 3 the spring 56 is utilized which acts between one of the upwardly projecting pieces 53 and the pin 57 carried by the plunger.

Extending outwardly from the underside 25 of the turntable 11 is a brake lever 58 which coöperates with certain brake mechanism to hold or release the turntable 11. The particular braking mechanism forms no part of the present invention and it is, therefore, 30 thought unnecessary to go into the detailed construction thereof. It will suffice to say that when the lever 58 assumes the position shown in dotted lines the turntable 11 is held against rotation and that when it assumes the position shown in full lines the turntable is released and permitted to be driven by the motor.

Mounted upon the base board of the phonograph is a plate 59 carrying the electro-magnets shown at 60. The armature for the electro-magnets is formed by the lever 61 pivoted to the plate 59 at 62 and having its outer end arranged to extend under the brake lever 58. A spring 63 is employed to hold the armature 61 in the position illustrated in Fig. 6 so that when the lever 58 is moved to the full line position in Fig. 3 it will be retained in such position until the armature 61 is attracted by the electro-magnets 60. The outer end of the armature 61 is beveled, as shown at 64, to permit movement of the lever 58 from its dotted line to its full line position. Carried by the plate 59 is a spring 65 which acts upon the lever 58 and tends to move the lever from its full line to its dotted line position, or from its non-braking to its braking position.

Referring now to the circuit connections shown in Fig. 3, 66 designates a battery one side of which is connected by means of the conductor 67 with the downwardly extending arm 28. The other side of the battery is connected through the conductor 68 with a switch 69 in turn connected to the brush 49. The brush 50 connects with the elec-

tro-magnets 21 through the conductor 70 and also connects with the electro-magnets 60 through the conductor 71. The other side of the electro-magnets 60 is connected with the brush 49 through the conductor 72. 70 The conductor 73 serves to connect the contact 31 with the electro-magnets 21.

The operation of the device is as follows: Assuming the several parts to be in the position shown in Fig. 3 and that a record is 75 being played by the phonograph, the tone arm 13 is moved gradually toward the center of the record, the stop lever 37 having been set before the record is played. The switch member 30 will engage the stop 38 80 when the stylus reaches the end of the record or a groove immediately adjacent the inner groove. The engagement between the switch member 30 and the stop 38 causes the former to swing about its pivot 29 to 85 provide electrical connection between the contacts 31 and 34, the indentations 32—32 and the projections 33—33 serving to afford a quick electrical connection after the switch 30 has been moved a certain predetermined amount relatively to its supporting arm 28. The closing of the contacts 31 and 34 provides an electric circuit as follows: from the battery 66 through conductor 67, through arm 28, through contacts 90 34 and 31, through conductor 73, electro-magnets 21, conductor 70, brush 50, through the ratchet 47, brush 49, through switch 69, and through conductor 68 to battery. Since the electro-magnets 21 are thus energized 95 100 the armature lever 61 is attracted and the reproducer lifted from the record.

To swing the tone arm from its innermost position to its outermost position slightly beyond the outermost groove in the record any suitable spring means may be employed, such for example as the spring mechanism shown at 74. A very light spring is employed so that no detrimental results accrue to the reproducing qualities of the phonograph. 110 The tone arm is swung outwardly, whereby the projection 75 of the switch member 30 engages the plunger 54 and is moved by such engagement to a position where the contacts 31 and 34 are separated. After the switch 30 has been moved to the position illustrated in Fig. 5 it cannot be swung about its pivot to a further extent with the result that the plunger 54 is moved in a direction toward the ratchet wheel 47 to advance the ratchet wheel one step. The breaking or separation of the contacts 31 and 34 deenergizes the electro-magnets 21 with the result that the reproducer is lowered and the stylus placed on the record slightly outside of the outer groove of the record. The spring 56 then acts to return the plunger 54 to its original position, and in doing so feeds the stylus to the outer groove in the record. I prefer to use slowly acting mag- 115 120 125 130

nets for operating the armature lever 26 so that the reproducer is brought into engagement with the record a certain time after the separation of the contacts 31 and 34. 5 The object of this arrangement is to permit the tone arm to operate the ratchet wheel 47 before the reproducer engages the record. The record is replayed in the manner above described until the ratchet wheel 47 has been 10 advanced a certain number of steps sufficient to bring the insulating plug 48 in contact with the brushes 49 and 50 to prevent the passage of current through the ratchet wheel. By referring to Fig. 3 it will be observed that the insulating plug will assume a position between the two brushes after the plunger 54 has been actuated five times. Therefore, upon the fifth actuation of the plunger the circuit is interrupted between 15 the brushes 49 and 50. At the fifth actuation of the plunger 54 the reproducer is brought into engagement with the record, as hereinbefore described, and the record repeated. When, however, the switch member 30 engages the stop 38 and closing of the contacts 31 and 34 takes place the following circuit will result: from battery 66 through conductor 67, contacts 31 and 34, conductor 73, electro-magnets 21, conductor 30 70, conductor 71, electro-magnets 60, and conductor 72 through switch to battery. The energization of the electro-magnet 60 releases the brake arm 58 with the result that rotation of the turntable is discontinued. Since the contacts 34 and 31 are closed and the circuit is provided through the electro-magnets 21 the reproducer will be lifted, as hereinbefore described, and will be returned to its original or starting position where the circuit for the magnets 21 will be interrupted and the reproducer permitted to engage the record which now is stationary.

The resistance of the electro-magnet 60 is such that when the brushes 49 and 50 contact with the ratchet wheel 47 a short circuit will be provided around the said electro-magnets and through the electro-magnets 21. When, however, the insulating plug is interposed between the brushes this short circuit is not permitted and the current is led through the electro-magnet 60. The finger piece 51, which is connected with the sleeve 46 and with the ratchet 47, 55 is provided with suitable indicia permitting the operator to set the ratchet wheel so that a certain record may be replayed automatically any number of times and then the machine automatically stopped. By the 60 employment of the switch mechanism of my invention it will be observed that a circuit is closed when the tone arm reaches a certain position with respect to the record and that the circuit is broken when the tone 65 arm reaches a certain other position with

respect to the record. I wish it to be understood that the switching mechanism may be varied to a considerable extent without departing from the spirit of the present invention.

70

In Fig. 8 I have shown a modified construction of electric switch for controlling the circuit of the electro-magnet for lifting the reproducer. In this figure, 80 illustrates a downwardly extending pin carried by the tone arm and 81 a lever pivoted at 82 to the base board of the phonograph. The lever 81 has two upwardly extending arms 83 and 84 arranged to be engaged by the pin 80. Mounted adjacent the arm 83 is a contact spring 85 arranged to coöperate with the arm 83 to produce an electric circuit. As the tone arm to which the pin 80 is connected moves to the left the projection 83 is engaged and the lever 81 swings 85 about its pivot 82 until connection is obtained between the spring 85 and the arm 83. This connection serves to close the electric circuit through the electro-magnets 21 which in turn lift the reproducer from the record. The tone arm then proceeds to swing in the opposite direction until the pin 80 engages the arm 84 and moves the lever 81 in a direction to cause disengagement of the arm 83 from the spring 85 to 90 interrupt the circuit. To provide a positive stop for the lever 81 in a counter-clockwise direction (Fig. 8) the pin 86 may be mounted on the base board and placed in the way of movement of the lever beyond 95 a certain predetermined amount. One of the teeth of the ratchet wheel 47 may be removed, if desired, and thereby provide means whereby a record may be continuously automatically repeated until the machine is stopped by the operator.

Having thus described my invention what I claim as new and desire to secure by Letters Patent of the United States is:

1. In a phonograph the provision of a 110 casing, a horizontally swinging tone arm, a sound reproducer carried by the tone arm and arranged to engage a record, electro-magnetic means for lifting the reproducer out of engagement with the record, electric 115 switching mechanism for controlling the operation of said electro-magnetic devices carried by the tone arm, and means for actuating said switching mechanism carried by the casing of the phonograph.

120

2. In a phonograph the provision of a base board, a horizontally swinging tone arm, a sound reproducer carried by the tone arm and arranged to engage a record, electro-magnetic devices for lifting the reproducer out of engagement with the record, electric switching mechanism for controlling the operation of said electro-magnetic devices carried by the tone arm, and means for actuating said switching mechanism 125 130

- carried by the base board of the phonograph.
3. In a phonograph the combination of a tone arm arranged to swing horizontally, 5 a goose neck pivoted to the outer end of the tone arm, a reproducer mounted on the outer end of the goose neck and arranged to engage a record, a lever carried by the tone arm for lifting the reproducer out of engagement with the record, an electro-magnet carried by the tone arm for actuating said lever, and an electric switch consisting of two elements one mounted on the tone arm and the other on a stationary 10 part of the phonograph for controlling the operation of the said electro-magnet. 70
4. In a phonograph the provision of a tone arm arranged to swing in a horizontal plane, a reproducer carried by the arm and 20 arranged to engage a record, electro-magnetic devices for lifting the reproducer from the record, and a switch for controlling the operation of said devices, comprising an element mounted on the arm, two 25 other elements on stationary parts of the phonograph, said switch being arranged to close an electric circuit through said electro-magnetic devices when the element on the arm engages one of the other elements, and 30 to maintain the circuit in a closed condition until the element on the arm engages the other of said two elements. 80
5. In a phonograph the provision of a tone arm arranged to swing horizontally, a 35 reproducer carried thereby and arranged to coöperate with the record to produce sound, electro-magnetic devices for lifting the reproducer from the record, an electric switch for controlling the operation of said devices 40 mounted on the tone arm, and a pair of switch actuating members carried by stationary parts of the phonograph, one of said members being arranged to close the switch and the other to open the switch upon engagement of the switch therewith. 85
6. In a phonograph the provision of a horizontally swinging tone arm, a reproducer, carried thereby and adapted to coöperate with the record to produce sound, electro-magnetic devices for lifting the reproducer from the record, an electric switch for controlling the operation of said devices 50 mounted on the tone arm, and a pair of adjustable switch actuating members carried 55 by stationary parts of the phonograph, one of said members being arranged to close the switch and the other to open the switch upon engagement of the switch therewith. 90
7. In a phonograph the provision of a horizontally swinging tone arm, a reproducer carried thereby, and arranged to coöperate with a record to produce sound, electro-magnetic devices for lifting the reproducer from the record, an electric switch for 60 controlling the operation of said devices 95
- mounted on the under side of the tone arm intermediate its ends, and a pair of switch actuating members arranged to actuate the switch when the tone arm assumes certain positions with respect to the record. 100
8. In a phonograph the provision of a reproducer arranged to engage a record, a record turn table, a brake for the turn table, means for lifting the reproducer from the record and for repeating the reproduction 75 of the record, and electro-magnetic devices for actuating the brake lever to stop rotation of the turn table, said electro-magnetic devices being controlled by the said repeating means. 80
9. In combination with a phonograph, a horizontally movable tone arm, a switch mechanism carried by the tone arm, an adjustable contact arranged to be advanced by the tone arm, a circuit breaking member carried by the contact, a pair of brushes arranged to engage said contact, a lifting electromagnet mounted on the tone arm and connected with said switch member, a brake control electro-magnet, circuit connections 90 for said switch member, said brushes and said electromagnets, and arranged so that upon operation of the switch member the circuit through the lifting magnet may be broken, and so that when the circuit breaking member is disposed between the brushes the brake control electromagnet will be energized. 95
10. In combination with a phonograph a horizontally movable tone arm, a switch 100 member, an adjustable contact arranged to be advanced by the tone arm, a circuit breaking member carried by the contact, a pair of brushes arranged to engage said contact, a lifting electromagnet, a brake control electromagnet, circuit connections for 105 said switch member, said brushes and said electromagnets, and arranged so that upon operation of the switch member the circuit through the lifting magnet may be broken 110 and so that when the circuit breaking member engages the brushes the brake control electromagnet will be actuated. 110
11. A phonograph comprising means for rotating a record, repeat mechanism, a stop 115 mechanism comprising an electromagnet, a battery connected in series with said electromagnet, a circuit shunting said electromagnet, and means controlled by said repeat mechanism for opening said shunt circuit 120 and thereby causing said electromagnet to actuate said stop mechanism. 120
12. A phonograph comprising a tone arm, a sound box pivoted on said tone arm, means for lifting said sound box relative to said 125 tone arm, means for moving the tone arm across the face of the record being played, to the beginning of the record, an adjustable stop for determining the time of operation of said lifting means and said moving 130

means, a second adjustable stop for causing said lifting means to lower said sound box when it has been moved to the beginning of the record, a stop mechanism, and means controlled by said last named stop for causing said stop mechanism to operate after the record has been played any desired number of times.

13. A phonograph comprising means for 10 rotating a record, a repeat mechanism comprising an electromagnet, a stop mechanism comprising an electromagnet, a tone arm,

and a switch mechanism actuated by the movement of said tone arm for closing an electric circuit through both of said magnets. 15

In witness whereof I hereunto subscribe my name this 13th day of September, A. D. 1917.
